UNITED STATES PATENT OFFICE.

JAMES L. MCQUARRIE, OF MONTCLAIR, NEW JERSEY, ASSIGNOR TO WESTERN ELECTRIC COMPANY, INCORPORATED, OF NEW YORK, N. Y., A CORPORATION OF NEW YORK.

AUTOMATIC SWITCHING APPARATUS FOR TELEPHONE-EXCHANGE SYSTEMS.

1,290,616.

Specification of Letters Patent.

Patented Jan. 7, 1919.

Application filed March 30, 1917. Serial No. 158,567.

To all whom it may concern:

Be it known that I, JAMES L. MCQUARRIE, a citizen of the United States, residing at Montclair, in the county of Essex and State of New Jersey, have invented certain new and useful Improvements in Automatic Switching Apparatus for Telephone-Exchange Systems, of which the following is a full, clear, concise, and exact description.

10 This invention relates to automatic switching apparatus for telephone exchange systems, and has for its object the provision of apparatus of this type which will be compact in structure, efficient in operation and low 15 in cost of production and maintenance.

In accordance with the general features of this invention, means are provided whereby a large number of multiple contacts accessible to any one of a plurality of brushes may, 20 without the use of bank or connecting wires, be grouped into a space of such area that any one of the brushes may be moved into engagement with any multiple contact within the bank in steps of a length possible to 25 attain easily and within a period of time found to be desirable and practical in such systems.

A form of switching device in which this 30 invention may be embodied is one in which a plurality of layers of multiple contacts are mounted in superimposed relation to each other and brushes are provided, each of which is adapted to be selectively moved to the said layers and transversely to the contacts of a selected layer. A well-known form 35 of brush operating mechanism may be used in which the brush may be selectively stepped to a desired layer in a direction at right angles to the planes of the layers, and rotated 40 transversely across the face of a selected layer to a desired contact set.

Another feature of this invention relates 45 to the construction of the switch bank whereby the contact strips may be mounted in a small space without sacrificing the clearance space between vertically adjacent strips between which the brushes have to move. In accordance with the feature of the invention the layers of multiple contacts are arranged 50 in two groups upon opposite sides of brush carrying shafts. The contact strips of each group are mounted in superimposed relation to each other and the contact strips in one

group are vertically staggered with respect to the contact strips of the other group. 55 Each brush shaft carries a single brush set and is adapted to be rotated in either direction to bring its brush set into engagement with the contacts of a strip to which the brush set may be moved by the vertical movement of the shaft. 60

In accordance with another feature of this invention the layers of multiple contacts are mounted upon hinged frame members which may be swung outwardly without disturbing 65 electrical connections to render the parts readily accessible for repair or replacement.

In the drawings, Figure 1 is a diagrammatic view of a switch embodying the features of this invention, illustrating also a circuit with which it may be used; Fig. 2 is a fragmentary plan view of the switch bank showing a set of brushes; and Fig. 3 is a plan view of the device showing a plurality of contact surfaces and coöperating brushes. 75

As shown in the drawings, the contact bank comprises a plurality of multiple contact strips 5, 5 and 6, 6 mounted in groups 7 and 8 upon opposite sides of a shaft 9, carrying brushes 10, 11 and 12. The multiple contact strips 5, 5 and 6, 6 are identical in construction and each comprises a plurality of longitudinally extending strips 13, 14, 15 of conducting material arranged in sets of one of each of the strips 13, 14, 15 to a set, the separate strips of each set being separated by insulating material, and the separate sets being insulated from each other. The strips 13 are each provided between their ends with a plurality of projecting contact surfaces 16, 16, the strips 14 with projecting contact surfaces 17, 17, and the strips 15 with projecting contact surfaces 18, 18. The contact surfaces 16, 17 and 18 of strips 13, 14 and 15 of the same set are longitudinally separated from each other while the contact surfaces 16, 17 and 18 of the corresponding strips of the several sets are arranged in the arc of a circle, the contact surfaces 16 being in the arc of a circle described by the brush 10, the contact surfaces 17 being in the arc of a circle described by the brush 11 and the contact surfaces 18 being in the arc of a circle described by the brush 12. 95

The multiple contact strips 5, 5 of the group 7 are mounted in a superimposed re- 105

lation to each other and the strips 6, 6 of the group 8 are mounted in a superimposed relation to each other. However, the contact strips 5, 5 are vertically staggered with respect to the contact strips 6, 6, this staggering being such that the vertically adjacent strips of opposite groups are one vertical step of the shaft 9 apart, while adjacent strips of the same group are two vertical steps of the shaft 9 apart. A plurality of brush shafts 9, 9 are provided, each carrying a set of the brushes 10, 11 and 12, each brush set being adapted to engage arcuate rows of contact surfaces of any multiple strip.

The several multiple contact strips 6, 6 comprising the group 8 situated on one side of the brush shafts 9, are arranged in proper spaced relation to each other and mounted in supporting members 61. There will be two of these supports, one at each end of the strips. The strips 6 are held firmly clamped in position by means of bolts such as 62, which pass through the over-turned ends of support 61 and pass between adjacent strips 6. Fastened to the support 61, by means of the bolt 63, is a hinge 64, one end of which is bent in the form of a circle and is loosely pivoted upon the stationary rod 65. By such an arrangement, the group of contact strips 6 is pivotally supported upon the rod 65 and it may be swung out away from the shafts 9 to permit of inspection and repair. Similarly the group 7, of contact strips 5 on the other side of the shafts 9, is mounted in a support 66 and pivoted to rod 65 by means of a hinge 67.

The mechanism for operating each of the brush shafts 9 embraces a vertical magnet 20 adapted to raise the shaft 9 step by step through the agency of a pawl 21 and teeth 22, 22 on said shaft. Rotation of the shaft 9 in either direction is obtained by means of rotary magnets 23 and 24, the magnet 23 operating through a pawl 25 and ratchet wheel 26 to rotate said shaft in a counter-clockwise direction, while the magnet 24 operates a pawl 27 and ratchet 28 to rotate the shaft 9 in a clockwise direction. A contact arm 30 carried by the shaft 9 in its vertical movement engages two sets of contacts 31, 31 and 32, 32 to control the respective circuits of the two rotary magnets 23 and 24. Vertical and rotary holding pawls 33 and 34 controlled by a release magnet 35 serve to hold the shaft 9 in its actuated position.

In Fig. 1, the apparatus of this invention is illustrated as a selector in which the brushes 10, 11 and 12 are adapted to be selectively stepped to a predetermined layer and to automatically hunt over the contacts of the layer until it finds an idle set of contacts.

Assuming as a specific example that the

subscriber at a station A wishes to obtain connection with a circuit terminating, say, in the fourth layer of the multiple contacts or the second one in group 8 and that he has already been connected with brushes or 70 wipers 37, 37, through the agency of a line switch, contacts of which are indicated at 40, 41, 42.

As soon as the subscriber A has had his line put into connection with the wipers 37, 75 37, a circuit will be completed for a double wound line relay 45, this circuit including the line wires of the subscriber A. Upon energization the line relay 45 will open a back contact 46 and close a front contact 47, 80 the closure of the front contact completing a circuit for a slow release relay 48, which, upon energization, opens a back contact 49, and closes a front contact 50. The closure of the front contact 50 closes a break in a circuit 85 for the vertical stepping magnet 20, which circuit also includes a horizontal off-normal contact HON, but so long as relay 45 remains energized, there is no flow of current over this circuit. As soon, however, as 90 the subscriber at station A operates his dial he will cause interruption of the circuit of the relay 45, causing it to deenergize and energize in response to these breaks. At each closure of the contact 46 in response to these 95 interruptions of the line circuit, however, a circuit will be completed for the vertical 98 magnet 20, which circuit includes the contact 46 of relay 45, contact 50 of relay 48 and HON contact. Assuming that the subscriber A dialed for four impulses, the vertical magnet will receive four impulses to step the brush shaft 9 up and bring the brushes 10, 11 and 12 thereon into a position to be moved over an arcuate row of contacts on the second strip 6 from the bottom of group 8. Upon the first deenergization 105 of the relay 45, in response to the operation of the sender, a slow-acting relay 51 was energized over a circuit including the front 110 contact 46 of relay 45 and front contact 50 of relay 48. This relay 51 remains energized during the sending of the impulses to maintain a circuit through its front contact 52 for an escapement magnet 53. Upon cessation 115 of impulses through the line relay 45, however, it will be maintained energized to open the circuit of the relay 51, thereby causing the deenergization of the escapement magnet 53 and the movement from their 120 first into their second positions of side-switch wipers 37, 37, 54, 55 and 56. As soon as the side switch wiper 56 is moved into its second position, a circuit will be completed for the rotary magnet 23, including the front 125 contact 47 of relay 45, side-switch wiper 56, the contact arm 30 carried by the shaft 9 and a contact 32, which is the fourth from the bottom and the second one of the group designated by the reference character 32, 130

This will energize the stepping magnet 23, which will draw up its armature to engage the pawl 25 with the ratchet wheel 26 to cause the shaft 9 to take one rotary step, 5 which will open contact HON and thereby interrupt the circuit of the vertical magnet 20. Each energization of the magnet 23 causes it to interrupt its own circuit at interrupter contact 57, thereby causing said rotary magnet to become energized and deenergized so long as side-switch wiper 56 remains in its second position. In its second position, the side-switch wiper 54 connects the escapement magnet 53 with a conductor 15 60, leading to brush 12, which may be used as a test brush. The first rotary step of the shaft 9 will land this brush on a contact 18 which, if any of the multiple contacts in that row are busy, will be free from ground connections, thereby maintaining the escapement magnet 53 deenergized. As soon, however, as brush 12 lands on a contact 18 which has a ground on it, the circuit through the escape magnet 53 will be completed and it 25 will be energized to cause the side-switch wipers 37, 37, 54, 55 and 56 to move from their second into their third positions. The escape magnet is arranged in the well-known manner to move the side switch to third position upon energization. The movement of the side-switch wiper 56 into its third position interrupts the energizing circuit through the rotary magnet 23. The movement of the side-switch arm 55 into its third position 30 35 closes a break in the circuit of the release magnet 35, which circuit also includes vertical off-normal contact VON.

Had the terminals sought been in one of the layers in the group 7 the operation 40 would have been precisely the same except that the contact arm 30 would have been stepped on one of the contacts 31 controlling the circuit of the stepping magnet 24.

What is claimed is:

45 1. In a switching mechanism, a terminal bank comprising a plurality of superimposed flat multiple contact strips, each of said strips comprising a plurality of multiple contact members having contact portions 50 at different positions along the length thereof, the contact portions at each of said positions being arranged in an arcuate row, the contact portions of all the rows of the same strip lying in a common plane, a movable brush at each of said positions arranged to coöperate with the contact portions at such positions, means for moving said brushes to select one of said contact strips, and means for rotating said brushes 55 60 to engage the contact portions of the selected strip.

2. In a switching mechanism, a terminal bank comprising a plurality of superimposed flat multiple contact strips, each of 65 said strips comprising a plurality of mul-

multiple contact members having integral contact portions at different positions along the length thereof, the contact portions at each of said positions being arranged in an arcuate row, the contact portions of all the 70 rows of the same strip lying in a common plane, a movable brush at each of said positions arranged to coöperate with the contact portions at such positions, means for moving said brushes vertically to select a 75 contact strip, and means for rotating said brushes into engagement with the contact portions of a selected strip.

3. In a switching mechanism, a terminal bank comprising two groups of flat multiple 80 contact strips, each strip comprising a plurality of multiple contact members having contact portions at different positions along the length thereof, the strips of one group being staggered with respect to the strips 85 of the other of said groups, movable brushes one for coöperating with the contact portions at each of said positions, and means for selectively moving said brushes to the contact strips of either of said groups and 90 into engagement with the contact portions of a selected strip.

4. In a switching mechanism, a terminal bank comprising two groups of flat multiple contact strips, each strip comprising a plurality 95 of multiple contact members having contact portions at different positions along the length thereof, the contact portions at each of said positions lying in a common plane, the strips of one group being staggered with respect to the strips of the other of said groups, movable brushes one for coöperating with the contact portions at each of said positions, and means to advance said brushes to select a contact strip in either 100 group and to further advance said brushes into engagement with the contact portions of the selected strip.

5. In a switching mechanism, a terminal bank comprising two groups of superimposed flat multiple contact strips, each strip comprising a plurality of multiple contact members having contact portions at different positions along the length thereof, the contact portions of each strip all lying in a 110 common plane, the contact strips of one group being vertically staggered with respect to the strips of the other group, movable brushes arranged at each of said positions to coöperate with the contact portions 115 at such positions, and means for moving said brushes to select a contact strip in either group and for moving said brushes into engagement with the contact portions of the selected strip.

6. In a switching mechanism, a terminal bank comprising two groups of multiple contact strips, the contact strips of each group being mounted in superimposed relation to each other and contact strips in one 130

group being staggered with respect to contact strips in the other group, and brushes each adapted to be selectively moved to strips of either group and transversely into engagement with contacts of a selected strip.

- 5 7. In a switching mechanism, a terminal bank comprising two groups of multiple contact strips, the contact strips of each group being mounted in superimposed relation to each other and the contact strips in one group being vertically staggered with respect to the contact strips of the other group, vertically and rotatably movable shafts mounted between said groups of contact strips, and a brush carried by each of said shafts adapted to be selectively moved to strips of either group in the vertical movement of said shaft and transversely into engagement with contacts of a selected strip.
- 10 8. In the rotary movement of said shaft.
- 15 9. In a switching mechanism, a terminal bank comprising two groups of multiple contact strips, the contact strips of each group being mounted in superimposed relation to each other and the contact strips in one group being vertically staggered with respect to the contact strips of the other group, a plurality of brushes, a shaft for each of said brushes mounted between said groups of contact strips, and selectively controlled means for each of said shafts for moving it vertically and rotating it in either direction.
- 20 10. In a switching mechanism, a terminal bank comprising two groups of multiple contact strips, the contact strips of each group being mounted in superimposed relation to each other and the contact strips in one group being vertically staggered with respect to the contact strips in the other group,

a plurality of brushes, a shaft for each brush, a stepping magnet individual to each of said shafts for moving it vertically to position its brush adjacent a strip of either group, a pair of electromagnets individual to each of said shafts for rotating said shaft 45 in either direction, and means controlled in the vertical movement of said shaft for determining which magnet of said pair will be effective.

10. In a switching mechanism, a terminal bank comprising two groups of multiple contact strips, the contact strips of each group being mounted in superimposed relation to each other and the contact strips of one group being vertically staggered with respect to the contact strips of the other group, a plurality of brushes, a shaft for each of said brushes, a vertical magnet individual to each of said shafts for positioning its brush adjacent a contact strip in either group, a pair of rotary magnets individual to each of said shafts, one adapted to rotate the shaft in one direction, the other adapted to rotate said shaft in the other direction, a circuit for each of said rotary magnets, and 65 circuit-controlling means controlled by said shaft in its vertical movement for separately controlling the circuits of said rotary magnets.

11. In a switching mechanism, a plurality of brushes, a shaft individual to each of said brushes, two groups of multiple contact strips located upon opposite sides of said brushes and shafts, and a hinged supporting frame for each group of said contact strips. 70 75

In witness whereof, I hereunto subscribe my name this 27th day of March, A. D. 1917.

JAMES L. McQUARRIE.
